UNITED STATES PATENT OFFICE.

JOHN PLATT, OF WARRINGTON, ENGLAND.

APPARATUS FOR CUTTING PILED FABRICS.

SPECIFICATION forming part of Letters Patent No. 603,224, dated April 26, 1898.

Application filed November 10, 1897. Serial No. 658,068. (No model.) Patented in England October 8, 1897, No. 23,068.

To all whom it may concern:

Be it known that I, JOHN PLATT, a subject of the Queen of Great Britain, residing at Lythgoes lane, Warrington, in the county of Lancaster, England, have invented certain new and useful Improvements in Connection with Apparatus for Cutting Piled Fabrics, (for which I have obtained a patent in Great Britain, No. 23,068, dated October 8, 1897,) of which the following is a specification.

My invention relates to improvements in connection with apparatus for cutting the pile of piled fabrics, and more particularly to those in which the knife is traversed along the cloth to be cut.

Prior to my present invention many arrangements have been devised for releasing the knife from the moving part which traverses it along the cloth to be cut, this release taking place whenever the knife pierces the cloth or encounters any obstruction; but all such arrangements have consisted of more or less complicated combinations of mechanism, including some device which comes into contact with the cloth in the event of the knife piercing the cloth.

My invention is intended to effect the release of the knife from the traversing power in the event of any increase in the normal resistance offered by the actual cutting of the pile of the cloth. Thus the knife will be released in the event of its piercing the cloth, or it may be released without the cloth being pierced if the cutting edge of the knife becomes dull, and thus offers increased resistance, or if the guide becomes broken or bent, so as not to be capable of guiding the knife, or if the knife meets with any obstruction which in the ordinary course would break it, or if the "knife and guide" turns out of the race into the uncut face of the cloth.

My invention enables an ordinary fustian-cutter's knife and guide free from any attached mechanism whatever to be used with safety, thus facilitating the work of the operator.

In carrying my invention into effect I prefer to employ an ordinary knife and guide placed on a traveling carriage, which I attach to the usual reciprocating cord or the like by an attachment which is strong enough

to drive the knife and cut the pile, but is at the same time weak enough to break or yield and so disconnect the carriage from the reciprocating cord, which moves it when any increase in the normal resistance occurs, the result being that the connection is broken or severed instead of the cloth being injured.

In the accompanying two sheets of drawings, Figure 1 is a side sectional elevation, and Fig. 2 a part plan, of a frame or table and apparatus to which my invention is applied for cutting piled fabrics. Figs. 3 and 4 are a longitudinal sectional elevation and plan, respectively, of the knife-carriage, illustrating one mode of attachment; and Figs. 5 and 6 are similar views to Figs. 3 and 4, respectively illustrating another mode of attachment.

In the views, *a* designates the piled fabric to be cut, which is stretched by means of two tightening-rollers *b* (one only of which is shown) over the spear or beam *c* at each end of the cutting-frame, and *d* is the traveling cord, which receives a reciprocating motion by means of a pair of pulleys *e*, (of which one is shown,) mounted one at each end of the frame and driven by hand or power, preferably by hand, in any convenient manner.

Instead of attaching the knife-carriage *f* firmly to the traveling cord *d* I pass the cord through a longitudinal groove *f'* in the carriage and keep it in position by rings or staples *g*, fixed to the carriage in such a manner that the cord may run freely through the groove *f'* and staples *g* without obstruction. I then attach the carriage *f* to the traveling cord *d* by a thread of ordinary thin sewing-cotton *h*, Figs. 3 and 4, or the like. The cotton thread or equivalent *h* is only of sufficient strength to actuate the carriage *f* with the knife and guide *i* when the knife is cutting the pile of the cloth *a* in the ordinary manner, but is weak enough to break if more than the normal resistance is encountered.

When the thread *h* breaks, the carriage *f*, on which the knife *i* is placed, ceases to be actuated by the traveling cord *d*, but remains stationary on the cloth while the cord *f* travels freely through the groove *f'*. The carriage and knife being thus arrested any damage to the cloth is prevented. The cotton

thread *h* or its equivalent may be proportioned in strength to the strength of the pile which it has to cut.

In the case of corduroys or similar strong fabrics a thread of linen or the like may be required, but for ordinary velvets and velveteens a thread of sewing-cotton is sufficient.

In Figs. 5 and 6 I show another mode of attaching the carriage *f* to the traveling cord *d*.

- 5 In this case an arm *j* is pivoted at *j'* to the carriage *f* and is retained normally in the position shown in Fig. 6 by means of a weak spring *k*, secured on the carriage. A thread-wire or equivalent *h* is firmly attached at one
- 15 end to the traveling cord *d* at a point in front of the carriage and its other end is formed into a loop which is placed over the pivoted arm *j*. In the event of the knife *i*, which is placed on the carriage *f*, meeting with more
- 20 than normal resistance the spring *k* yields and allows the free end of the arm *j* to move forward, when the loop of the thread or equivalent *h* slips off the end of the arm *j*, and so disconnects the carriage *f* with the knife *i*
- 25 from the traveling cord *d*.

Although I have only shown and described two forms of attachment, it will be obvious to any practical man familiar with the art that many other forms might be employed without departing from the nature of my invention, which consists, essentially, in the use and application of a frangible attachment which will break or yield in the event of more resistance being met with than is sufficient to cut the

- 30 pile without injury to the cloth.
- 35 In order to prevent the carriage *f* from slipping forward on the reciprocating cord *d*, a

knot may be tied on the said cord with or without a small washer *m* behind it and large enough not to enter the groove *f'* in the carriage.

Having now particularly described and ascertained the nature of my said invention and in what manner the same is to be performed, I declare that what I claim is—

1. The combination with a knife and guide, and means for actuating the same, of a frangible attachment to the actuating means, said frangible attachment being strong enough to actuate the knife when cutting under normal conditions, but weak enough to allow the knife to become detached when more than the normal resistance is encountered, substantially as and for the purposes hereinbefore set forth.

2. The combination with a knife and guide, knife-carriage, and means for reciprocating the same, of a frangible attachment connected at one end to the actuating means and at the other end to the traveling-knife carriage, substantially as and for the purposes hereinbefore set forth.

3. The combination with a traveling-knife carriage and means for actuating the same, of a frangible attachment connected at one end to the carriage and at the other end to the actuating means, substantially as and for the purposes hereinbefore set forth.

In witness whereof I have hereunto set my hand in presence of two witnesses.

JOHN PLATT.
